O. H. Myrick, Inventor.

UNITED STATES PATENT OFFICE.

OWEN HARVEY MYRICK, OF WINNFIELD, LOUISIANA.

SASH-HOLDER.

SPECIFICATION forming part of Letters Patent No. 635,339, dated October 24, 1899.

Application filed April 1, 1899, Serial No. 711,367. (No model.)

To all whom it may concern:

Be it known that I, OWEN HARVEY MYRICK, a citizen of the United States, residing at Winnfield, in the parish of Winn and State 5 of Louisiana, have invented a new and useful Sash-Holder, of which the following is a specification.

This invention relates to window-sash holders of that class which are carried by the side 10 rails of the sash and are adapted to frictionally engage the window-jamb, whereby the sash may be held in any adjusted position.

The object of the present invention is to provide certain improvements in the construction 15 of the several parts and to provide means for varying the frictional engagement of the device with the window-jamb to take up wear.

To these ends the present invention consists in the combination of parts, as will be hereinafter more fully described, shown in the accompanying drawings, and particularly pointed out in the appended claims.

In the drawings, Figure 1 is an elevation of 25 a part of a window frame and sash having the improved holder applied thereto. Fig. 2 is a detail longitudinal sectional view through the side rail of the sash, showing the engagement of the device with the window-jamb. Fig. 3 is a transverse sectional view on the line xx . Fig. 2. Fig. 4 is a detail perspective view of 30 the device removed from the sash.

Corresponding parts are designated by like 35 reference characters in all the figures of the drawings.

Referring to the accompanying drawings, the window-frame is designated by the numeral 1 and the sash by the numeral 2, and each is of common or ordinary construction. Only one side of the sash and window-frame 40 is shown, but it will be understood that a pair of the devices is used, one mounted upon each side rail of the sash.

By reference particularly to Figs. 2 and 3 it will be seen that the side rail of the sash is 45 provided with a central recess 3, opening outward through the outer edge of the sash toward the jamb 4 of the window-frame. Extending transversely through the sash-rail, having their opposite ends projecting, respectively, into the recess and beyond the inner edge of the rail, is a pair of rods 5. Arranged within the recess and against the back thereof

is a plate 6, receiving the pins therethrough, and a similar plate 7 is fitted to the outer ends of the rods and adapted to close the mouth of the recess. Each rod is provided with a coiled spring 8, encircling the same and located between the two plates 6 and 7. The opposite ends of each spring are connected to the respective plates 6 and 7 by passing the end of 60 the spring through the plate and bending it back against the opposite face thereof, as at 9. Thus the plates 6 and 7 are yieldingly connected together. It will be noted that the outer ends of the rods 5 are reduced in diameter, forming annular stop-shoulders 10, which are adapted to engage the inner face of the plate 6 to prevent the rods from slipping through the plate. Intermediate of the ends of the yielding plate 7 is provided a slot or 65 recess 11, in which is mounted a friction-roller 12, which projects a suitable distance beyond the outer face of the plate. The inner ends of the rods 5, which project beyond the inner edge of the sash-rail, are also reduced in diameter, forming the annular stop-shoulders 13, and fitted to the reduced inner ends of the rods is a plate 14, flush against the stop-shoulders. A bolt 15 is passed transversely through the side rail of the sash from the recess, having its head 16 engaging the back wall of the recess and its threaded end slidably extending through the plate 14, intermediate of the rods 5. The threaded end of the bolt, which projects beyond the plate 14, is provided with 70 a thumb-nut 17.

In the operation of the device the several parts thereof are assembled as hereinbefore described and the sash is fitted between the jambs of the frame. The thumb-nut 17 is 75 then tightened up against the plate 14, which engages the shoulders 13 of the rods 5 and forces the same outward. As the shoulders 10 near the outer ends of the rods 5 engage the plate 6 the latter is forced outward and carries with it the yielding plate 7 until the friction-roller 12 is properly engaged with the adjacent jamb 4 of the window-frame. The device being thus adjusted, the sash may be forcibly moved up or down, but will be 80 held at any point by the frictional engagement of the roller 12 with the window-jamb 4. The purpose of having the roller 12 yieldingly mounted is to permit of the same giv-

ing sufficiently to facilitate the moving of the window-sash, as will be understood.

As the window-jamb or the roller becomes worn the thumb-nut may be tightened to pre-
5 serve the proper tension upon the friction-
roller, and by loosening the nut the plate 6
may be permitted to settle back into the in-
closing recess, whereby the tension upon the
roller may be relieved, and thus the device
10 may be adjusted as desired.

The present device provides a practical
and useful sash-holder which obviates the
employment of cords and balance-weights.
The parts are substantial in structure and
15 are completely inclosed within the sash-rail,
and thereby protected against dust, &c. Be-
ing inclosed within the sash-rail and project-
ing beyond one edge only thereof adjacent
20 to the window-glass, the device is located out of
the way, yet in a convenient position for ad-
justment, and presents no projections upon
the face of the sash, which is very objection-
able.

Changes in the form, proportion, size, and
25 the minor details of construction within the
scope of the appended claims may be re-
sorted to without departing from the spirit
or sacrificing any of the advantages of the
present invention.

30 Having thus described the invention, what
is claimed is—

1. A sash-holder, comprising opposite
plates, parallel rods connecting the plates,
one of the latter being fixed, and the other
35 slidable upon the opposite ends of the rods,
a friction device carried by the slidable plate,

an intermediate plate slidable upon the rod,
a tension device bearing in opposite direc-
tions against the adjacent faces of the slid-
able plates, stops provided upon the rods, lo-
40 cated between the fixed and intermediate
plates, and in engagement with the latter,
and adjusting means carried by the fixed
plate and controlling the slidable intermedia-
te plate, substantially as and for the purpose 45
set forth.

2. A sash-holder, comprising opposite
plates, parallel rods connecting the plates,
one of the latter being fixed, and the other
slidable upon the opposite ends of the rods, 50
a friction device carried by the slidable plate,
an intermediate plate slidable upon the rod,
a tension device bearing in opposite direc-
tions against the adjacent faces of the slid-
able plates, stops provided upon the rods, lo-
55 cated between the fixed and intermediate
plates, and in engagement with the latter,
and a bolt or rod slidable through the fixed
plate, having a head located at its inner end
for engagement with the intermediate slid-
60 able plate, and a thumb-screw provided upon
the outer threaded end of the bolt or rod and
adjustably bearing against the outer face of
the fixed plate, substantially as and for the
purpose set forth.

65 In testimony that I claim the foregoing as
my own I have hereto affixed my signature in
the presence of two witnesses.

OWEN HARVEY MYRICK.
